UNITED STATES PATENT OFFICE.

FREDERIC S. CONVERSE, OF LYONS, NEW YORK.

WAGON END-BOARD.

No. 800,079.

Specification of Letters Patent.

Patented Sept. 19, 1905.

Application filed April 18, 1903. Renewed May 24, 1905. Serial No. 262,084.

To all whom it may concern:

Be it known that I, FREDERIC S. CONVERSE, a citizen of the United States, residing at Lyons, in the county of Wayne and State of New York, 5 have invented certain new and useful Improvements in Wagon End-Boards, of which the following is a specification.

This invention relates to wagons, and more especially to the end-gates used thereon; and 10 the object of the same is to produce such a latching means for the gate that it may be opened or closed by the operator without necessitating his going from one side of the wagon to the other, and the gate may be set 15 at various angles.

The invention consists in the details set forth below and illustrated in the accompanying drawings, wherein—

Figure I is a side view with the gate closed. 20 Fig. II is a side view with the gate open. Fig. III is a longitudinal sectional view with the gate in an intermediate position. Fig. IV is a detail showing how the movement of the latch raises the hanger. Fig. V is a view 25 of the latch from the rear, showing the hanger in section. Fig. VI is a detail of the hanger and its bracket. Fig. VI^a is a perspective detail showing another form of bracket.

In the drawings the numeral 1 designates 30 the wagon-body.

2 represents side-boards which may or may not be employed, and 3 represents strap-irons on the wagon-body leading to a hinge-rod 4, which is countersunk in the inner end of the 35 gate for the purpose of making a close-fitting joint when the gate is open or closed and which connects with other strap-irons 5 on the end-gate. The latter preferably has a wooden bottom 6, on which the operator will 40 not slip, and metal sides 7, the whole being suitably braced by cross-pieces 8 and otherwise. The sides are spaced so as to pass outside the wagon-body and the side-boards 2 when the gate is closed, as in Fig. I, and the 45 bottom of the end-gate preferably stands at right angles to its inner end, as illustrated. The upper edges of the sides may be notched, as at 9, so that when closed the notches will pass over the latch mechanism, which is located on the outer side of the wagon-body, as 50 seen in Fig. I.

The latch 10 is pivoted on a pin 11, which may be braced, as at 12. The upper end of the latch is bent outward into a handle 13. 55 Its body has a notch 14, adapted to engage a stud or pin 15 on the end-gate when the latter

is closed, and its lower end is turned inward in a lip 16, as best seen in Fig. V. This latch and the hanger described below are in reverse at the opposite sides of the wagon, and a description of one will suffice for both. 60

The hanger 20 is in reality a hook with several notches 21 in its lower edge. Its inner end is pivoted to a plate or bracket 22 by the pin 11, and near said pivotal point 65 there is a stop 23 on the hanger, Fig. VI, or there are stops 23^a on the bracket to prevent the hanger 20 from falling too low or being raised too high, as best seen in Fig. VI^a. The lip 16 of the latch projects inward beneath the hanger, so that, as best seen in Fig. IV, the hanger is raised when the handle of the latch is pressed to the rear, while the forward movement of said handle does not cause the depression of the latch. 70

The parts are preferably all of metal except as otherwise indicated, and the size, proportions, and exact construction of the details are immaterial. 75

When the gate stands closed, as seen in Fig. I, the notches 14 engage the studs 15, and because the latches stand horizontal the hangers may fall to an oblique position, as seen in dotted lines. To open the gate, the operator passes behind the wagon and raises 80 both handles simultaneously. This disengages the notches 14 from the studs 15, and the gate commences to turn from the position of Fig. I to the position of Fig. III. The lower edges of the hangers ride along upon 85 studs or pins 25 at the inner corners of the gate, and unless the handles 13 are kept raised the first of the notches 21 will engage these studs, so as to hold the gate in an intermediate position, as shown in dotted lines in Fig. 90 I. Obviously the operator can thus open the gate to any desired extent. To again close it, it is only necessary to lift its outer end to the extent required. This operation is produced by the fact that the latch and hanger 95 are pivoted on the same pivot, and the lip 16 on the former permits a certain lost motion between the turning of the two members. 100

In Fig. V is best seen a projection 26, which is formed on the latch below its pivot and extends outward in a direction opposite to the lip 16. This projection may be, and preferably is, employed, and its function is to hold the latch in a horizontal position, as seen in Fig. I, which it does by coming up against 105 the brace 12; yet when the latch is raised, as seen in Fig. IV, this projection passes around 110

the end of the brace 12, and therefore does not interfere with the movements of the latch.

What is claimed as new is—

1. In a latch for end-gates, the combination 5 with the gate hinged to the wagon-body and having two studs projecting from its side; of a latch proper pivoted to the wagon-body and having a notch adapted to engage the outer stud when the gate is closed, a hanger mounted on the same pivot and having notches adapted to engage the inner stud when the gate is open, and connections between the latch and hanger for raising the latter by the movement of the former but permitting a 15 certain lost motion between them, as and for the purpose set forth.
2. In a latch for end-gates, the combination with the gate hinged to the wagon-body and having two studs projecting from its side; of 20 a latch proper pivoted to the wagon-body and having a notch adapted to engage the outer stud when the gate is closed, a hanger mounted on the same pivot and having notches adapted to engage the inner stud when the 25 gate is open, and a lip on the latch standing under the hanger for disengaging the hanger

from its stud when the latch is raised but permitting lost motion when the latch is depressed.

3. In a latch for end-gates, the combination 30 with the gate hinged to the wagon-body and having studs; of hangers having notches adapted to engage said studs, brackets to which said hangers are pivoted, and stops thereon for limiting the rise and fall of the 35 hangers.

4. In a latch connecting two members, the combination with the latch proper pivoted to one member and having a projection adjacent its pivot, and a brace leading from said member to the outer end of the pivot and adapted to be engaged by said projection to support the latch; of a second member connected with the first, and a stud on this member adapted to engage the notch of the latch. 40 45

In testimony whereof I affix my signature in presence of two witnesses.

FREDERIC S. CONVERSE.
